END GATE

Filed Sept. 8, 1922

2 Sheets-Sheet 2

Gustav Inventor Klomhaus

Attorney

UNITED STATES PATENT OFFICE.

GUSTAV KLOMHAUS, OF PLAINFIELD, ILLINOIS.

END GATE.

Application filed September 8, 1922. Serial No. 586,933.

To all whom it may concern:

Be it known that I, GUSTAV KLOMHAUS, a citizen of the United States, residing at Plainfield, in the county of Kendall and State of Illinois, have invented certain new and useful Improvements in End Gates, of which the following is a specification.

This invention relates to end gates and the primary object of this invention is to provide an improved means for associating an end gate with a wagon body, whereby the end gate will be positively locked in position and thereby prevent the loss of the gate through the jarring loose of the fastening device therefor and the consequent loss of material carried by the wagon.

Another object of the invention is to provide an improved end gate in which a section thereof can be raised to permit the unloading of the wagon without the necessity of removing the entire end gate from the wagon.

A further object of the invention is to provide a novel means for associating the channel guides with the wagon body, whereby the inner faces thereof will be flush with the inner faces of the wagon body, so that the said channel guides will not interfere with the unloading of the wagon.

A further object of the invention is to provide an end gate for wagons embodying a pair of sections, one of the sections having means for positively engaging the channel guides to prevent movement thereof and carrying means for permitting the raising of the other section to permit the easy unloading of the wagon body, said means including a lever which is associated with the first mentioned section in such a manner that when the other section is in its lowered position, the lever will engage the same and prevent accidental movement thereof.

A further object of the invention is to provide an improved end gate embodying an upper section, a lower section, means for positively locking the upper section in position, and a lever connected with the upper section having cables connected with the lower section, so that upon movement of the lever the lower section will be raised.

A further object of the invention is to provide a novel means for associating the terminals of the cable with the lower section of the end case whereby the cables can be readily removed from engagement with the lower section when so desired.

A still further object of the invention is to provide an improved end gate of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a perspective view of the improved end gate showing the same associated with a wagon body, the lower section of the end gate being shown in its raised position. Figure 2 is a rear elevation of the end gate showing the same associated with a wagon body, the lower section of the end gate being shown in its lowered position.

Figure 3 is a horizontal section, taken on the line 3—3 of Figure 2.

Figure 4 is a vertical section, taken on the line 4—4 of Figure 2.

Figure 5 is a detail vertical section through one of the guide pulleys for the lifting cables, taken on the line 5—5 of Figure 2.

Figure 6 is an enlarged horizontal section taken through the improved end gate on the line 6—6 of Figure 2.

Figure 7 is an enlarged fragmentary detail elevation illustrating the means for connecting one of the lifting cables with the lower section of the end gate.

Figure 8 is a vertical section taken on the line 8—8 of Figure 7.

Figure 9 is a detail side view of a pulley carried by the lever for operating the lifting cables for the lower section of the end gates, and

Figure 10 is a front elevation of the same.

Referring to the drawings in detail, where-in similar reference characters designate corresponding parts throughout the several views, the letter A generally indicates the improved end gate; and B, a wagon body with which the same is associated.

The wagon body B can be of the ordinary type or of the type illustrated in my co-pending companion application, for wagon bodies, filed Oct. 18, 1922, Serial No. 595,342. The wagon body B as shown, includes the lower wall 5 and the side walls 6 and 7.

The end gate A includes the main portion

10 and an auxiliary portion 15, which can be used when the wagon body is provided with a top section as shown in the drawings. The main portion 10 includes a top section 11 and a lower section 12, which are slidably associated with the body B by means of channel guides 13 and 14. The top portion 15 consists of a single section and is slidably associated with the top portion of the wagon body by means of guides 16 and 17. The sections 11 of the main portion 10 of the end gate and the upper or auxiliary portion 15 are each provided with locking means 18 and 19 respectively for engaging the channel guides 13 and 14 and 16 and 17. The sections 11 and 12 have operatively connected therewith means C for permitting the raising and lowering of the lower section without the necessity of removing the entire end gate 20 from the wagon body B.

The channel guides 13 and 14 are preferably associated with the side walls 6 and 7 of the wagon body B in such a manner that the inner faces thereof will be flush with the inner faces of the walls 6 and 7 so that the same will not interfere with the unloading of the wagon. As shown these guides 13 and 14 include side plates 20, which are secured, in any preferred manner such as by bolts 21, to the outer faces of the side walls 6 and 7. The inner faces of the side plates 20 are provided with inwardly extending spaced parallel flanges 22 and 23. These flanges are disposed in spaced parallel relation to the rear edges of the side walls 6 and 7 and the flanges 22 form in connection with the rear edges of the side walls 6 and 7 guides for the upper section 11 of the main portion 10 of the end gate, while the flanges 22 and 23 form guides for the lower section 12 of the main portion 10 of the end gate. The upper channel guides 16 and 17 are secured to the top section of the wagon body B and consist of side plates 24 and inwardly extending flanges 25. The side plates 24 are secured to the outer faces of the top section of the wagon body. The inwardly extending flanges 25 are in direct alignment with the flanges 22 and the flanges 25 in connection with the rear edge of the walls of the top section of the wagon body B form guides for the upper portion 15 of the end gate A.

The locking means 18 for the upper section 11 of the main portion 10 of the end gate includes a pair of channel members 30, which are disposed adjacent to the opposite ends of the section 11 and these channel shaped members 30 rotatably slidably support locking bolts 31, the outer terminals of which are provided with hook shaped heads 32. The inner ends of the rotatable and sliding bolts 31 are provided with operating handles 33. The side plates 20 of the channel guides 13 and 14 are provided

with elongated openings 34 which are adapted to receive the hook shaped heads 32 of the locking bolts 31. In operation of the locking members 18, the handles 33 of the locking bolts 31 are grasped and turned so as to position the hook heads 32 in parallelism with the elongated opening 34 and the bolts are then slid outwardly until the hook shaped head 32 protrudes through the openings, after which the handles are turned down. This positions the heads 32 in engagement with the outer surface of the channel guides 13 and 14. When it is desired to remove the portion 11 it is merely necessary to raise the handles 33 and then draw the bolts inwardly toward each other which will move the hook shaped head 32 from out of the openings 34.

The locking means 19 for the upper portion 15 of the tail gate A is constructed identically the same as the locking means 18 and the locking means 19 includes rotatable and sliding bolts 35 which are slidably and rotatably mounted in suitable guides 36 carried by the portion 15 adjacent to the terminals thereof. The top portion of the body B is provided with rearwardly extending plates 37 which are provided with elongated openings 38 for the reception of the hooked terminals 39 of the bolt. The means for operating the bolts 35 is the same as the means for operating the bolts 31. It is evident of course that after the bolt has been operated, the upper enlarged portions 15 and 10 of the end gate can be removed.

The means C utilized for operating the lower section 12 of the main portion 10 of the end gate A includes an elongated operating lever 40, the outer end of which is provided with an offset extension 41 which forms the handle for operating the lever. The inner end of the lever is provided with a polygonal shaped opening 42 for the reception of the polygonal shaped extension 43 formed on the double pulley or drum 44 which is rotatably mounted upon a supporting bolt 45 carried by the upper section 11 of the lower portion 10 of the tail gate A. The supporting bolt 45 can have mounted thereon if so desired, a suitable bearing sleeve 46 for supporting the double pulley or drum 44. A nut 47 is threaded upon the bolt 45 in order to retain the operating lever 40 and the pulley or drum 44 on the bolt and a suitable wear washer may be interposed between the nut 47 and the pulley or drum 44. Eyes 48 and 49 are formed on the double pulley or drum 44 at diametrically opposed points and these eyes 48 and 49 have secured thereto the lifting cables 50 and 51. These cables 50 and 51 are trained over suitable guide pulleys 52 carried by the upper section 11 adjacent to the channel guide members 30. The lower terminals of the cables 50 and 51 are secured to suitable eye bolts 53 which 130

have threaded thereon nuts 54. The outer face of the lower section 12 of the main portion 10 of the end gate A has secured thereto angle brackets 55, the upper horizontal portions of which are provided with slots 56 in which are adapted to be positioned the eye bolts 53 and the nuts 54 are adapted to engage the lower faces thereof. If so desired, the walls of the slotted portion 56 of the bracket may be rabbeted for receiving the nuts 54 in order to prevent the accidental rotation thereof. In order to prevent the accidental displacement of the eye bolts 53 from out of the slots 56, the horizontally disposed portions of the angle brackets 55 slidably receive pins 57 which are adapted to extend across the slots and thus close the open ends thereof. In order to prevent loss of the pins 57 the same can be retained in place by suitable cords 58 which can be secured in any preferred manner to the angle brackets 55. The lifting cables 50 and 51 are strained about the double pulley or drum 44 in opposite directions so that upon movement of the double pulley or drum by the lever 40, the cables 50 and 51 will be wound thereabout and thus effectively raise the lower section 12. The inner face of the offset handle portion 41 of the operating lever 40 has secured thereto an inwardly extending bolt or holding pin 60 which is adapted to engage the upper surface of a leaf spring 61 which is secured to an angle bracket 62 carried by the outer face of the lower section 12 of the main portion 10 of the end gate A, when the section 12 is in its lowermost position. The leaf spring 61 has formed therein a centrally disposed transversely extending rib 63 which is adapted to receive the bolt 60 when the section 12 is in its lowermost position and the lever 40 is in its lowered position as shown in Figure 2 of the drawings. It is evident that when the lever is in the position shown in Figure 2 of the drawings, that movement thereof will be prevented and thus the lower section 12 will be firmly held in its lowered position against accidental movement. The outer end of the bolt or holding pin 60 can be provided with an enlarged head 64, which is adapted to engage the inner edge of the leaf spring 61. It also can be seen that the bolt 60 will also engage the upper edge of the gate A and thus hold the lever in its raised position as clearly shown in Figure 1 of the drawings. When the section 12 is in its lowered position, the same rests upon the upper surface of the bottom wall 5 of the wagon body B and it can be seen that the lower wall 5 is extended slightly beyond the side walls 6 and 7 of the wagon body. When it is desired to remove the contents of the wagon body, it is merely necessary to swing the lever 40 to its uppermost position as shown in Figure 1 of the drawing which will wind up the cables 50 and 51 and thus raise the section 12 which will permit grain or other material carried by the wagon body to be readily shoveled out of the same.

When it is desired to remove the main portion 10 of the end gate from the wagon body, it is merely necessary to operate the bolts 31 heretofore described and lift the portion upward from out of the channel guides 13 and 14.

From the foregoing description, it can be seen that an improved end gate has been provided which is of exceptionally simple and durable character, and which will effectively permit the unloading of the wagon without removing the end gate from position and which will effectively prevent the loss of grain from the wagon.

Changes in details may be made without departing from the spirit or scope of this invention; but,

I claim:

- An end gate comprising an upper section, a lower section, releasable locking members carried by the upper section for engaging a wagon body, a lever rotatably carried by the upper section, cables detachably connected to the lower section adjacent to the opposite ends thereof, means operatively connecting the cables with the lever whereby upon movement of the lever in one direction the lower section will be raised.
- An end gate for wagons comprising an upper section and a lower section, means for locking the upper section to a wagon body, a lever rotatably carried by the upper section, means detachably connecting the lever with the lower section for raising and lowering of the lower section upon movement of the lever, and means carried by the lever for engaging the lower section to hold the same in its lowermost position against movement.
- An end gate for wagons comprising an upper section and a lower section, means for releasably connecting the upper section with a wagon body, a rotatable lever carried by the upper section, means operatively connecting the lever with the lower section for permitting the raising thereof upon operation of the lever, a leaf spring carried by the lower section, and a bolt carried by the lever for engaging the leaf spring when the lower section is in its lowered position for holding the lever against accidental movement and the lower section in its lowermost position against movement.
- The combination with a wagon body having channel guides secured thereto, an end gate slidably mounted in said guides, including an upper section, rotatable and slidably mounted in said guides, and a lower section slidably mounted in said guides, and

- means detachably connecting the upper and lower sections together and acting to raise and lower the lower section in relation to the upper section.
5. The combination with a wagon body including side walls and channel guides carried by the side walls, of an end gate including an upper and lower section slidably mounted in said guides, means carried by 10 an upper section for releasably engaging the guides to prevent movement of the upper sections, a drum rotatably carried by the upper section, a lever connected with said drum, cables secured to the drum on opposite sides thereof, and means connecting the terminals of the cable to the lower section.
15. The combination with a wagon body including side walls, a pair of channel guides secured to the side walls, of an end gate slidably mounted in the channel guide members including an upper and a lower section, means carried by the upper section for engaging the channel guide members to hold the same against accidental movement, a drum rotatably carried by the upper section, 20 a lever operatively connected with the drum, guide pulleys secured to the upper section, a pair of lifting cables secured to the drum at diametrically opposite points and trained about said cables, means detachably securing the lower ends of the cables to the lower section, an angle bracket secured to the lower section, a leaf spring secured to the upper face of the angle bracket having a centrally disposed indentation 25 therein, and an inwardly extending pin carried by the outer end of the lever arranged to engage in the indentation in said leaf spring to hold the lever against movement and the lower section against accidental 30 movement when in its lowered position.
